HOSPITAL BED ATTACHMENT

Theobald Kluglein, Valley Stream, N. Y.

Application July 16, 1946, Serial No. 683,865

6 Claims. (Cl. 5—61)

1

This invention relates to cooperative attachments applicable to hospital or other beds.

More particularly the invention relates to attachments for handling invalids and patients requiring medical attention.

Among the benefits and advantages of the invention are the following. Patients may be handled with greater facility and with less pain and discomfort. It enables attendants to shift a patient from one position lying on the bedding to a position above it so as to facilitate the use of various accessories. Also, facilitates turning of a patient or invalid while in a reclining position so that the patient or invalid may rest on the bed lying on his or her right or left side, back or stomach. It also enables attendants to readily carry a patient to or from the bed without an extra litter or stretcher.

The nature of the invention and its distinguishing features and advantages will appear when the following specification is read in conjunction with the accompanying drawings, in which—

Fig. 1 is a side elevational view of a bed selected to show the attachments of the present invention applied thereto by way of example.

Fig. 2 is a sectional view taken on the line 2—2 of Fig. 1.

Fig. 3 is a sectional view taken on the line 3—3 of Fig. 1, portions being broken away.

Fig. 4 is a detail sectional view.

Fig. 5 is a sectional view taken on the line 5—5 of Fig. 4.

Fig. 6 is a perspective view of one of the attachment guides, a portion thereof being broken away.

Fig. 7 is a perspective view of a part of the bracket which supports the rocker arm.

Fig. 8 is a plan view of the flexible stretcher.

Fig. 9 shows a portion of the stretcher which receives one of the buttons of the rotatable frame, a portion of which is shown in Fig. 10.

On reference to Figs. 1, 2 and 3, it will be seen there is shown a hospital bed 10 including a head end 11, a foot end 12 and a mattress 13 supported by the spring structure of any suitable type.

In accordance with the invention the head end 11 has an attachment or frame structure 14 rotatably mounted thereon at the inside, suitable attaching means 15 consisting of a flanged block having an arbor 16. The block 15 is vertically slidably in a guide 17 secured to the head end 11 on the inside and centrally thereof, as shown in Fig. 3. A set screw 18 carried by the guide 17 and extending through the head end 11 engages the block 15 to hold the structure 14 in any

vertically adjusted position. The structure 14 is substantially semi-circular and has a series of buttons or the like 19 thereon. The frame structure is adapted to receive the arbor 16 projecting through it and a wing-nut 20 in threaded engagement with the arbor serves for retaining the frame structure 14 in the desired angular position of adjustment. The arbor 16 is disposed parallel to the longitudinal axis of the bed. Handles 21 on the structure 14 serve for turning it on the arbor 16 into different positions of adjustment when the nut 20 is loosened.

Also in accordance with the invention a second attachment is secured to the foot end 12 to cooperate with the frame structure 14. This second attachment includes a frame structure 22 substantially similar to the structure 14. The structure 22 is mounted for adjustment on an axis paralleling the longitudinal axis of the bed and also in an arc toward and away from the structure 14 on a horizontal axis disposed at a right angle to the longitudinal axis of the bed. This is accomplished by the use of an angular arm 23 having an arcuate portion 24 and a portion 25. The lower end of the portion 25 is pivotally connected, as at 26 with the lower end of a flanged bracket 27 vertically adjustable in a guide 28 secured to the foot end 12. A set screw 29 carried by the bracket 27 engages in one of the holes or dents 30 in the guide 28 to secure the bracket in the desired vertically adjusted position. The bracket 27 has a guide 31 for the arcuate portion 24, the latter extending through said guide 31 as shown. The underside of the arm portion 24 has gear teeth 32 which mesh with a gear 33 mounted to rotate in the guide 31. The gear 33 meshes with a reducing pinion 34 fast on a shaft 35 supported by the guide 31. A pivoted pawl 36 on the guide 31 is engageable with a notched disk 37 connected with the shaft of the gear 33 to prevent the arm 23 from moving out of an adjusted position. The shaft 35 has a crank handle 38 for turning the shaft 35 and its pinion 34. The frame structure 22 is rotatably mounted on the inner end of the arcuate portion 24. A wing-nut 40 in threaded engagement with said portion 24 serves to clamp the structure 22 in different angular positions of adjustment with respect to said portion 24. The structure 22 has a series of spaced buttons 41 like the buttons 19. Handles 42 on the structure 22 serve for adjusting it as stated.

In accordance with another feature of this invention use is made of a stretcher 43 for carrying and placing a patient or invalid on the mat-

tress 13 of the bed. The stretcher 43 is also adapted to be connected with the structures 14 and 22 for the purpose of shifting the patient or invalid from one position lying on the mattress or bedding to a position above it, and also for turning the patient or invalid so that the patient or invalid may rest on the mattress lying on his or her right or left side, back or stomach. The stretcher 43 is made of stout fabric or other soft flexible material. It has reinforced hand-holds 44 at the four corners. A flap 45 is held in a closed position in an opening in the stretcher by a suitable slide fastener 46, and the flap may be opened to enable the use of various accessories for obvious purposes when the stretcher is elevated in a taut or stretched condition. The stretcher has a series of keyholes 47 in each of the reinforced end portions to receive the buttons 19 and 41 on the frame structures 14 and 22, respectively.

With the patient on the stretcher while on the bed, the stretcher may be engaged with the buttons 19 and 41. The patient may then be elevated by releasing the pawl 36 and then turning the crank handle 38. This causes the stretcher 43 to become taut and being anchored at the opposite ends to the structures 14 and 22, the patient is sustained in an elevated position above the mattress. In Fig. 1 the dot-and-dash lines 48 indicate the stretcher 43 taut; the dot-and-dash lines 49 indicate the stretcher 43 slack contacting the mattress; and the dot-and-dash lines 50 indicate the stretcher 43 detached from the structures 14 and 22 and lying on the mattress 13.

Additional buttons 51 on the structures 14 and 22 may be provided to retain the stretcher 43 flatwise horizontally to enable attendants or a doctor to readily perform special operations on the patient. The buttons 19 and 41 retain the stretcher 43 like a hammock to keep the patient from rolling off the bed. However, by adjusting the structures 14 and 22 the patient may be turned to lie on one side or the other.

It is to be understood that the invention is not restricted to the precise provision and arrangement of parts shown and described, as details of construction may be modified and rearranged without departing from the spirit of the invention, the scope of which is limited only by the terms of the appended claims.

I claim:

1. The combination with a bed, of cooperative frame structures, means mounting one of said structures on the head end of the bed for adjustment about an axis paralleling the longitudinal axis of the bed, means mounting the other of said structures on the foot end of the bed for adjustment about an axis paralleling the longitudinal axis of the bed and also for movement in an arc toward and away from said head end, a

stretcher consisting of a panel of stout flexible material having the opposite ends thereof connected with said frame structures respectively, and means to fixedly secure each of said frame structures with respect to the bed.

2. The combination with a bed, of a patient sustaining stretcher made of flexible material, means on the foot and head ends of the bed to which the opposite ends of said stretcher are connected, said means including a frame connected with one of said ends of the stretcher adjustable to a position to elevate the stretcher while sustaining a patient with respect to the bed bottom, and said frame also being adjustable to lower the stretcher onto said bed bottom while sustaining the patient.

3. Bed attachments for raising, lowering and turning a patient, comprising foot and head end frames, means for rotatably supporting the head end frame on a bed, a bracket adapted to be fixedly secured to the bed, a pivoted arm on the bracket, means rotatably supporting the foot end frame on said arm, means connected with the frames operable to adjust each of said frames about its axis of rotation, means to secure each frame in the adjusted position, power applying means on the bracket and the arm to cause pivotal movement of said arm to raise and lower the foot end frame, means to secure the arm in its adjusted position, an oblong stretcher of flexible material, and coacting means on said frames and stretcher detachably connecting the stretcher with the frames.

4. Bed attachments as set forth in claim 3, wherein each of said frames is substantially semi-circular.

5. Bed attachments as set forth in claim 3, wherein the pivot of said arm is disposed horizontally and at a right angle to the longitudinal axis of the bed.

6. Bed attachments as set forth in claim 3, wherein said power applying means comprises a portion of said arm which is arcuate and has gear teeth, a rotatably mounted shaft carried by said bracket, gearing operated by said shaft and meshing with said teeth, and a crank connected with said shaft to rotate it.

THEOBALD KLUGLEIN.
